UNITED STATES PATENT OFFICE

SAM P. WHIDDEN, OF BARTOW, FLORIDA

DESIGN FOR A COMBINED FUEL BASKET, FIRE-TOOL SUPPORT, AND FLOOR LAMP
OR THE LIKE

Application filed January 28, 1930. Serial No. 34,316. Term of patent 7 years.

To all whom it may concern:

Be it known that I, SAM P. WHIDDEN, a citizen of the United States, residing at Bartow, in the county of Polk and State of Florida, have invented a new, original, and ornamental Design for Combined Fuel Basket, Fire-Tool Support, and Floor Lamp or the like, of which the following is a specification, reference being had to the accompanying drawing, forming part thereof.

Figure 1 is a view in front elevation of

the device constructed in accordance with the present design.

Figure 2 is a view in side elevation of the same.

Figure 3 is a fragmentary view in top plan.

I claim:—

The ornamental design for a combined fuel basket, fire tool support and floor lamp or the like substantially as shown.

SAM P. WHIDDEN.
